CLAIM

The ornamental design for a stethoscope, as shown and described.

DESCRIPTION

FIG. 1 is a front elevational view thereof;
FIG. 2 is a back elevational view thereof;
FIG. 3 is a right elevational view thereof;
FIG. 4 is a left elevational view thereof;
FIG. 5 is a top plan view thereof;
FIG. 6 is a bottom plan view thereof;
FIG. 7 is a right perspective view of the stethoscope; and,
FIG. 8 is a left perspective view of the stethoscope.
The broken lines are included for the purpose of illustrating portions of the stethoscope that form no part of the claimed design.

1 Claim, 8 Drawing Sheets(56)
